UNITED STATES PATENT OFFICE.

JOHN C. EDWARDS, OF BROOKLINE, MASSACHUSETTS, ASSIGNOR TO DRAPER COMPANY, OF HOPEDALE, MASSACHUSETTS, A CORPORATION OF MAINE.

SHUTTLE-CHECKING MEANS FOR LOOMS.

SPECIFICATION forming part of Letters Patent No. 778,646, dated December 27, 1904.

Application filed July 8, 1904. Serial No. 215,707.

To all whom it may concern:

Be it known that I, JOHN C. EDWARDS, a citizen of the United States, and a resident of Brookline, county of Norfolk, State of Massachusetts, have invented an Improvement in Shuttle-Checking Means for Looms, of which the following description, in connection with the accompanying drawings, is a specification, like characters on the drawings representing like parts.

This invention relates to means for checking and stopping the shuttle of a loom when "home" in the shuttle-box, so that the shuttle may be positioned as nearly as possible at the same point pick after pick; and the invention has for its object the production of novel means for exerting checking pressure upon the shuttle, whereby the checking and stoppage of the same will be efficiently and accurately accomplished.

In the present embodiment of my invention the checking pressure is exerted upon the shuttle independently of the binder, which accordingly is mainly employed to control the usual protector mechanism with which looms are equipped, and a light protector-spring can be used. This enables the shuttle to be readily moved in the shuttle-box to accommodate itself to properly receive an incoming filling-carrier when the loom is provided with mechanism to insert a fresh filling-carrier into the shuttle when necessary to replenish the filling.

In order to adapt my novel checking means to such an automatic loom, which may be of the "Northrop" type, as embodied in United States Patent No. 529,940 and of others of later date, I have provided means whereby the shuttle is automatically relieved of the checking pressure when such filling replenishment is effected.

The construction and operation of the pressure-producing means is such that any tendency of the shuttle to rebound is neutralized.

The various novel features of my invention will be fully described in the subjoined specification, and particularly pointed out in the following claims.

Figure 1 is a top or plan view of one end

of the lay of a loom with a shuttle-box thereon and having one embodiment of my invention applied thereto, the shuttle being shown as boxed, and the construction is arranged for the replenishing-box of an automatic filling-replenishing loom. Fig. 2 is a transverse sectional detail on the line 2-2, Fig. 1, showing also a portion of the replenishing mechanism. Fig. 3 is a top or plan view of the pressure producing or checking member detached. Fig. 4 is a perspective view of the angularly-movable support on which the said member is eccentrically pivoted, and Fig. 5 is a detached plan view of the bunter by or through which said support is angularly moved to relieve the shuttle from checking pressure when filling replenishment is effected.

The lay A³, picker P, binder B, fulcrumed on the lay at b¹ and acted upon by the usual binder-finger b, carried by the protector rock-shaft b', Fig. 2, the binder having a swell B' and the shuttle-box having a fixed front wall 17, cover-plate 17^x, and back wall 30, may be and are all of usual construction and operate in well-known manner.

In Fig. 2 I have shown a portion of a filling-feeder or hopper F to support a series of filling-carriers or bobbins b¹⁰, a transferer f' to insert them one by one into the automatically self-threading shuttle S when the lay is at or near its front center, the dog m, which operates the transferer being moved into the path of the bunter C² on the lay when filling replenishment is called for all substantially as in the patent referred to, the movement of the dog m being controlled by the rock-shaft d' in well-known manner.

The lay is provided with two bearing-brackets 1 and 2, extended rearwardly therefrom (see Fig. 2) to support an upright angularly-movable support or stud 3, (shown separately in Fig. 4,) the reduced lower end of the stud extending below the bracket 2 and having secured to it by a set-screw 4 the hub 5 of an L-shaped bunter 67. The arm 6 of the bunter is long enough to extend the bunter well in 95 toward the center of the loom, so that the arm 7 thereof, which is extended forward beneath the lay, will not be in the way of the picker-

stick or of a filling-carrier when ejected from the shuttle. The arm 7 is provided with an upturned shoulder 8 to abut against a bearing 9 secured to the under side of the lay, the arm 7 sliding loosely through this bearing. A spring 10, Figs. 1 and 2, connected at one end to the bearing and at its other end to the arm 7, acts to hold the shoulder 8 against the bearing in the normal position shown. The stud 3 has a circular head 11, which rests on the top of the bracket 1, and an eccentric pivot pin or post 12 is upturned from this head. This eccentric forms the center on which the pressure-producing member turns, said member being shown as a rather thick circular disk 13, provided with an eccentric hole 14, Fig. 3, to loosely receive the post 12, the checking member being retained on the post in any suitable manner, as by a nut 13^x screwed onto the post. An arm 15, extended rearwardly from the cam-like checking member 13, is connected with one end of a strap 16, which passes outward around the picker P and is fastened at its other end to the front wall 17 of the shuttle-box, and a spring 18 (shown in Fig. 1) is fastened at one end to the back of the lay and at its other end to the arm 15 to swing the latter in the direction of the arrow 19 until the arm engages a stop-pin 20 on the bracket 1. When the picker is thrown inward to eject the shuttle S from the box, the strap 16 is slackened and the spring 18 instantly turns the member 13 on its center 12, releasing the shuttle and retaining the checking member inoperative until the shuttle again enters the box. When the impact of the incoming shuttle upon the picker throws it outward, the strap 16 is tightened, and it acts through the arm 15 to turn the check 13 on 40 its pivot 12 in a direction opposite the arrow 19 and into locking engagement with the side wall of the shuttle.

When the pressure-producing member 13 is in its inoperative position, its periphery is moved out of the path of the shuttle owing to the eccentricity of the member 13; but when the latter is turned into operative position, as described, its periphery is brought into engagement with the side of the shuttle with an 50 increasing pressure as the cam is turned farther round until the shuttle is stopped.

It will be seen that the direction of rotation of the checking member is opposite to the movement of the shuttle, and if the latter tends to rebound it will then cause the checking member to increase its wedging action and effectually prevent any rebound.

The binder B is cut away or recessed, as at 35, (see dotted lines, Fig. 1,) to permit the 60 checking member 13 to pass through and engage the shuttle-wall, the checking action of said member being directly exerted upon the shuttle and operating wholly independent of the binder.

65 The binder serves as an initial check upon

the incoming shuttle and it controls the usual protector mechanism for the loom; but inasmuch as the main checking and stopping of the shuttle is effected by the member 13 a light binder-spring can be utilized.

70 In practice the retracting-spring 18 will be made strong enough to instantly turn the checking member in the direction of the arrow 19, Fig. 1, to release the shuttle when the picker is thrown inward to throw the shuttle 75 out of the box.

So far as the operation of the checking means applies to an ordinary loom or to the non-replenishing shuttle-box of an automatic loom it will be manifest that the pivot on 80 which the checking member 13 is mounted eccentrically may be rigidly mounted on the lay; but when the loom is provided with mechanism to automatically insert a filling-carrier in the shuttle the checking means at the re-plenishing shuttle-box must include provision for automatically relieving the shuttle from 85 checking pressure during replenishment.

90 In an automatic loom when filling replenishment is called for the usual controlling rock-shaft d' , Fig. 2, is turned in the direction of arrow 40 and elevates a dog d^2 into position to engage the bunter-arm 7 and push the latter back as the lay approaches front center, the shuttle having been checked just 95 before. The upright stud 3 is angularly moved in its bearings and the post 12 is moved rearwardly and somewhat toward the outer end of the lay, thereby carrying bodily the checking member 13 away from the side wall of 100 the shuttle and relieving the latter of checking pressure, so that it is free to move and accommodate itself to the incoming filling-carrier when filling replenishment is effected. By this movement of the post 12 I avoid tightening 105 the strap 16, it being manifest that it would not do to tighten the strap in order to release the check, because such tightening would act to pull the picker inward and push the shuttle away from the outer end of the shuttle-box. By means of the set-screw 4 the bunter 110 6 7 can be adjusted on the stud 3 to increase or decrease the angular movement of said stud to relieve the shuttle of the checking pressure.

115 The rather broad peripheral face of the checking member prevents any scoring or cutting action on the side of the shuttle when the checking pressure is exerted thereupon. By the adjustment between the bunter and the stud 3 I am also enabled to vary the checking action, for if the outward movement of the picker upon impact with the shuttle is substantially constant the adjustment of the pivot-pin 12 away from the shuttle-path will tend to decrease the checking pressure and 120 adjustment toward the shuttle-path will increase it, as then the wedging action of the checking member upon the shuttle will be augmented.

125 My invention is not restricted to the precise 130

construction and arrangement herein shown and described, as the same may be varied or modified in various particulars by those skilled in the art without departing from the spirit and scope of my invention.

Having fully described my invention, what I claim as new, and desire to secure by Letters Patent, is—

1. A loom having, in combination, a lay provided with a shuttle-box, a binder, and independently-mounted means actuated by or through impact of the incoming shuttle to exert checking pressure upon the latter independently of the binder.
2. A loom having, in combination, a lay provided with a shuttle-box, a binder, and means mounted independently thereof and actuated by or through impact of the incoming shuttle to directly engage and exert checking pressure upon the same.
3. A loom having in combination, a lay provided with a shuttle-box, a rotative pressure-producing device and means positively actuated by or through impact of the incoming shuttle to turn said device oppositely to the direction of movement of the shuttle, and cause it to engage and check the latter.
4. A loom having, in combination, a lay provided with a shuttle-box, a binder, and a rotative pressure-producing device mounted independently of the binder and actuated by or through impact of the incoming shuttle to directly engage and check the same independently of the binder.
5. A loom having, in combination, a lay provided with a shuttle-box, a binder, a rotative checking-cam adapted to be brought into direct engagement with the shuttle to check the same, means to operate said cam by the incoming shuttle, and a spring to return the cam to inoperative position.
6. A loom having, in combination, a lay provided with a shuttle-box, a rotative, eccentrically-mounted pressure-producing member, and means to rotate the same to exert checking pressure upon the shuttle as the latter nears the end of its stroke.
7. A loom having, in combination, a lay provided with a shuttle-box, a binder having a recess, a pressure-producing member extended through the recess to at times engage and exert checking pressure upon the shuttle, and means to operate said member as the shuttle approaches the end of its stroke.
8. A loom having in combination, a lay provided with a shuttle-box, means to automatically insert a fresh filling-carrier in the shuttle when the lay is at or near front center, a binder, means operated by or through impact of the incoming shuttle to exert checking pressure thereupon independently of the binder, and means to automatically relieve the shuttle of such pressure while the fresh filling-carrier is inserted.
9. A loom having, in combination, a lay pro-

vided with a shuttle-box, means to automatically insert a fresh filling-carrier, in the shuttle when the lay is at or near front center, a rotative member having a convex face to directly engage and exert checking pressure upon the incoming shuttle, means to operate such member as the shuttle approaches the end of its stroke, and means to automatically relieve the shuttle of such pressure while a fresh filling-carrier is inserted.

10. A loom having, in combination, a lay provided with a shuttle-box, a rotative, eccentrically-mounted pressure-producing member, means to rotate the same to exert checking pressure upon the shuttle as it approaches the end of its stroke, and means to automatically relieve the shuttle of such pressure when the lay is at or near front center.

11. A loom having, in combination, a lay provided with a shuttle-box, an upright, angularly-movable stud mounted on the lay, a checking-cam eccentrically mounted to rotate on said stud, means to rotate the cam into checking engagement with the shuttle, as the latter approaches the end of its stroke, and independent means to effect automatically angular movement of the stud to thereby retract the cam bodily and relieve the pressure upon the shuttle when the lay is at or near front center.

12. A loom having, in combination, a lay provided with a shuttle-box, an upright, angularly-movable stud mounted on the lay, a checking-cam eccentrically mounted to rotate on said stud, means actuated by or through impact of the incoming shuttle to turn the cam and thereby exert checking pressure upon the shuttle, a bunter rigidly attached to the stud, and means to engage the bunter when the lay is at or near front center and effect angular movement of said stud, to thereby withdraw the cam bodily and relieve the shuttle of checking pressure.

13. A loom having, in combination, a lay provided with a shuttle-box, means to automatically insert a fresh filling-carrier in the shuttle, a rotative pressure-producing device, a support upon which it is eccentrically mounted, means actuated by impact of the incoming shuttle to rotate said device and exert checking pressure upon the shuttle, and independent means to move the support when a fresh filling-carrier is inserted and thereby retract bodily the pressure-producing device, to relieve the shuttle of checking pressure.

14. A loom having, in combination, a lay provided with a shuttle-box, a binder, an upright stud mounted rotatably on the lay and having an eccentric pivot-post, a pressure-producing disk rotatably mounted thereon and having a rearwardly-extended arm, an attached spring to turn said disk into inoperative position, means connected with said arm to turn the disk into checking engagement with the shuttle when the latter approaches

the end of its stroke, and independent means to automatically turn the stud and thereby bodily retract the disk to relieve the shuttle from checking pressure.

- 5 15. A loom having, in combination, a lay provided with a shuttle-box, a binder, a disk eccentrically pivoted on the lay and having a rearwardly-extended arm, an attached spring to turn said disk into inoperative position, and 10 means connected with the arm and actuated by or through impact of the incoming shuttle to turn the disk against the action of the spring and into checking engagement with the shuttle.
- 15 16. A loom having, in combination, a lay provided with a shuttle-box, a binder, a rota-

tive cam - like pressure - producing device turned by or through the action of the incoming shuttle into checking engagement with the same, the direction of rotation of such device being opposite to the movement of the shuttle, and means to effect rotation of said device in such direction, whereby any tendency of the shuttle to rebound serves to increase the checking action of such device. 20 25

In testimony whereof I have signed my name to this specification in the presence of two subscribing witnesses.

JOHN C. EDWARDS.
